UNITED STATES PATENT OFFICE.

LYMAN DODGE, OF NEWBURYPORT, MASSACHUSETTS.

DOOR-HINGE.

1,291,791.

Specification of Letters Patent.

Patented Jan. 21, 1919.

Application filed March 7, 1918. Serial No. 221,025.

To all whom it may concern:

Be it known that I, LYMAN DODGE, a citizen of the United States, residing at Newburyport, in the county of Essex and State 5 of Massachusetts, have invented certain new and useful Improvements in Door-Hinges, of which the following is a specification.

This invention relates to door hinges and the primary object thereof is to provide a 10 gravity hinge of this character which is so constructed as to cause the door to raise a predetermined distance upon being opened and which when the door is released will automatically return the same to a closed position.

Another object of the invention is to provide the hinge with anti-friction means to insure the smooth operation of the same when returning the door to closed position 20 after the same has been opened thus preventing any jarring action as the door descends from its open or elevated position.

Other objects of the invention as well as the construction and arrangement of the 25 several parts thereof will be more readily understood from the following description and accompanying drawings in which drawings:—

Figure 1 is a side elevation of my invention proved hinge in applied position.

Fig. 2 is an edge view of the same, and

Fig. 3 is a side elevation partly in section.

In the drawings wherein I have shown 35 my invention in its preferred embodiment I have used the numeral 1 to designate a stationary support such as the wall of a room or a building and 2 a door to be hingedly connected to said support. The hinge 40 which comprises the subject matter of the present invention includes a leaf or plate 3 which is adapted to be attached to the support 1 and is provided with the usual knuckle 4. This knuckle 4 is provided with 45 a socket 5 which opens into its upper end and is adapted to receive the reduced lower end 6 of a pintle 7. This pintle 7 has a spirally twisted groove 8 extending upwardly along its entire length. A second 50 plate indicated at 9 is adapted to be attached to the door and this plate is likewise provided with a knuckle 10 which is adapted to receive the pintle 7 and rests upon the upper end of the knuckle 4. This knuckle 10 is 55 provided with an integral enlargement 11 which is equipped with a threaded bore

forming a socket for the reception of a set screw 12. This set screw 12 is formed with an enlarged threaded shank 13 which is adapted to be received in the bore of the 60 enlargement 11 and this shank opposite the head is reduced as at 14 to receive a friction roller 15. The set screw is normally arranged as shown in Fig. 3 with the friction roller 15 projecting into the interior of 65 the knuckle 10 and positioned between the opposite walls of the spiral groove 8.

In the operation of the hinge assuming that the friction roller 15 is engaged with the groove 8 as shown in Fig. 3, it will be 70 obvious that as the door 2 is moved outwardly or opened this roller will travel upwardly along the spirally twisted groove thus causing the knuckle 10 to ride up upon the pintle 7 and elevate the door. When 75 the door is released the weight of the same will cause the friction roller to travel downwardly along the inclined groove and will thus automatically return to a closed position. When, however, it is desired to 80 use the hinge as an ordinary hinge it is merely necessary to turn the set screw in a direction to withdraw the friction roller from engagement with the spiral groove.

Having shown only a preferred embodiment of my invention it will be understood that I do not limit myself to the exact details of construction and arrangement shown thereby, but reserve the right to make such alterations as I deem advisable provided of 85 course that the same follow within the scope of the appended claims and do not depart from the spirit of the invention.

I claim:—

1. A hinge, comprising a pair of plates, 95 knuckles carried by said plates, a pintle carried by one of said knuckles and adapted to be received in the other knuckle, said pintle being provided with a spirally twisted groove, a set screw carried by said last mentioned knuckle, and a friction roller secured to said set screw and adapted to travel in said groove.

2. A hinge, comprising a pair of plates, 105 knuckles formed on said plates, a pintle carried by one of said knuckles and adapted to be received in the other knuckle, said pintle being equipped with a spirally twisted groove, an enlargement formed on said last mentioned knuckle and provided with an in- 110 teriorly threaded bore, a set screw engaged in said bore, and a friction roller carried by

the inner end of said set screw, and adapted to travel in said slot.

3. A hinge, comprising a pair of plates, knuckles formed on said plates, a pintle carried by one of said knuckles and adapted to be received in the other knuckle, said pintle being provided with a spirally twisted groove, a socket integral with said last mentioned knuckle, a set screw threaded into said socket, and provided with a reduced extension and a friction roller rotatably mounted upon said extension and adapted to travel in said groove.

4. A hinge comprising a pair of hinge plates, a knuckle carried by one of said plates and equipped with a socket opening into one end thereof, a pintle having one end reduced and disposed in said socket and provided with a spiral groove extending from the reduced end to the opposite end thereof, a second knuckle carried by the remaining

hinge plate and surrounding the grooved portion of said pintle, and a roller carried by said second knuckle and mounted to rotate in said groove.

5. A hinge comprising upper and lower knuckles, a pintle carried by said lower knuckle and fitting into said upper knuckle, said pintle being provided with a spiral groove extending the full length of said upper knuckle, a pin extending transversely through the upper knuckle and provided on its inner end with a roller adapted to travel in said groove, said pin and roller being laterally removable through the upper knuckle to permit separation of said knuckles.

In testimony whereof I affix my signature in presence of two witnesses.

LYMAN DODGE.
